SHOULDER PAD

Walter Riedler and Berthold Mechur, New York,
N. Y., assignors, by mesne assignments, to
Perma-Fit Shoulder Pad Co., Inc., New York,
N. Y., a corporation of New York

Application July 8, 1949, Serial No. 103,578

8 Claims. (Cl. 2—268)

1

This invention relates to a structurally and functionally improved shoulder pad for use in connection with garments, such as coats, dresses, etc.

It is an object of the invention to furnish a shoulder pad which will properly fit into an armhole and support and contour the garment in a manner such that the material of the latter will not gather.

A further object is that of providing a unit of this type which may readily be employed by tailors and other artisans so that the sleeve may be properly supported and draped with respect to the body of the garment and adjacently to the armhole of the latter; the use of such pad requiring but minimum skill.

An additional object is that of providing a pad which will embody simple design and structure and accordingly be capable of quantity manufacture treatment so that the unit may be sold at nominal cost.

With these and other objects in mind, reference is had to the attached sheet of drawings illustrating one practical embodiment of the invention and in which:

Fig. 1 is a prospective view of a complete pad;
Fig. 2 is the covering portion or member prior to the assembly of the part;

Fig. 3 is a plan view illustrating the units in process of assembly;

Fig. 4 is a plan view of the complete pad; and

Fig. 5 is a somewhat enlarged transverse sectional view taken along the line 5—5 and in the direction of the arrows in Fig. 4.

Referring primarily to Fig. 2, the numerals 10 and 11 indicate sections of a covering formed of any desired material and which sections may be joined to each other by a line of so-called flatlock stitching 12 or any other joining stitch. That line of stitching as illustrated preferably extends in an arcuate direction. As is apparent while different sections 10 and 11 may in many instances be preferred, a single material section might provide the cover.

Projecting portions 13 form a part of the covering in opposite side edges thereof. Slits 14 and 15 may define these projecting portions. These slits extend at angles with respect to each other. The slits 14 and 15 provide openings in the covering adjacent the projecting portions 13. These openings are defined by the edges of the slits 14 and 15. Extending laterally across the covering is a fold line for the covering. The slits 14 and 15 terminate at or near this fold line. Below the slits 14 and 15 the covering portions are

extended as 16 and the opposed edges of these areas may be formed with slits 17 should this be desired. Regardless of whether the covering is formed of more than one section or not, it is to be understood at the present time that the left hand area as viewed in Fig. 2 indicates the rear portion of the finished pad and the right hand area 11, the front portion thereof.

Layers 18, 19 and 20 are placed upon the covering after the latter is inverted as shown in Fig. 3. The pad is then folded upon itself along the lines defined by the rear edges of the projecting portions 13 and the slits 14 and 15 as well as the line indicated by dot and dash in Fig. 3. The fold line extends from one edge of the covering to the other. The filling or shaping material indicated by the layers 18, 19 and 20 may be of a nature taught in our United States Letters Patent No. 2,523,720, issued September 26, 1950. It is apparent that different filling materials might be employed and that if a soft pad is desired stitching might be resorted to in order to secure the parts against movement without employing heat or pressure. In any event, it is preferred to employ a staple 21 or the equivalent thereof to initially couple the parts against movement and prior to any final shaping operation. As will be understood if pressure is employed then dry or wet heat may be resorted to.

In any event, a pad should ultimately result which will have the appearance of that shown in Figs. 1, 4 and 5. This is accomplished by folding the covering layer as in Figs. 2 and 3 upon itself along the lines indicated by dot and dash in the latter figure. Under these circumstances, the curved central line 12 will in the upper and lower sections or layers of the cover be aligned. Especially if pressure and heat are employed then a properly contoured and curved unit will result as in Fig. 1 and as taught for example in the afore identified application for patent. The projecting portions 13 will extend beyond the adjacent parts 16 and 17, as defined by the slits 14 and 15. This has been indicated in dotted lines in Fig. 4. The dot and dash line indicates the extension of the fold line to the edge of the covering. In Fig. 5 one of the projecting portions 13 is shown. The extension of the fold line to the edge of the covering is also shown. The extension of the projecting portion 13 beyond the fold line is shown. It is apparent that ample material will thus be available for securing the pad to those portions of the garment which are adjacent to the armhole. Also, as indicated in Figs. 1, 4 and 5 a line of stitching 22 may be employed to retain or

assist in retaining the parts of the assembly against displacement.

As will be understood the outer edge portion of the pad will preferably be curved throughout substantially its entire length, despite the straight area of fold indicated by dot and dash lines in Fig. 3. This will be because of the padding material and the shaping operation which will occur to achieve this result. As shown in the several views the pad is of substantially triangular formation when viewed either in initially assembled condition or in its final form. This configuration may, of course be varied in certain particulars. In a shoulder pad the important area, with relation to the fit in its respective garment, lies along the outer edge of the shoulder pad which is to be fastened to the arm hole portion of the particular garment. In the shoulder pad of the invention this outer edge is formed along the fold line, on which line the shoulder pad is folded on itself. The important area is the fold of the shoulder pad and the resultant side edge of the pad. This outer edge portion of the pad is curved and the axis of this curved edge is shown as line A—A in Fig. 5. This axis is in the same general direction as the long dimension of the shoulder portion of the garment into which the shoulder pad is to be set.

As mentioned above, the projecting portions 13 which extend outwardly of the shoulder pad in general are formed by the slits 14 and 15. Edges of the slits 14 and 15 form a part of the curved outer edge of the shoulder pad after the shoulder pad is folded into its final form as shown in Figs. 1, 4, and 5. The axis A—A extends along the long dimension of the shoulder pad. The projections 13 extend outward of the shoulder pad from a line that is perpendicular to the axis A—A. Thus, the shoulder pad fits into the shoulder and the arm hole of the garment.

In an ordinary pad of this type the outer second edge portion contacts the line of the armhole at only a single point. This is usually adjacent to the upper zone of the armhole. Due to the transverse and laterally curved configuration of the outer edge of a pad constructed in accordance with present teachings, this end edge will align with the edge of the armhole throughout the entire length of the former. Therefore, the top zone of the cloth of a garment does not gather or fall into pleats incident to the application of the pad. The longer slit 14 being incorporated in the rear portion or zone of the pad a proper length is provided and the material of the garment will also not tend to gather at this point.

Thus, among others, the several objects of the invention as specifically afore noted are achieved. Obviously numerous changes in construction and rearrangement of the parts might be resorted to without departing from the spirit of the invention as defined by the claims.

We claim:

1. A shoulder pad comprising in combination a sheet of material, a fold in said sheet upon itself, an upper layer of said sheet formed by said fold, a lower layer of said sheet formed by said fold, said fold extending transversely across said sheet and interposed between said layers, a pad of material contained within the upper and lower layers of said folded sheet material, an edge of said pad of material abutting the inner surface of said fold, slit defining edges extending into said sheet at an angle to said fold, and a projecting portion of said sheet adjacent

one of said edges and extending from said fold.

2. A shoulder pad including in combination a sheet of material, a fold in said sheet upon itself, an upper layer of said sheet formed by said fold, a lower layer of said sheet formed by said fold, said fold extending transversely across said sheet and interposed between said layers, a pad of material positioned between the upper and lower layers of said folded sheet of material, slit defining edges in said sheet on each side of said shoulder pad, said edges formed at an angle to said transverse fold, a first set of said edges in said lower layer extending in one direction from said transverse fold and a second set of said edges in said upper layer extending in the opposite direction from said fold whereby said first set of edges in said lower layer form angles with their respective edges in the second set of edges in the upper layer.

3. A shoulder pad as claimed in claim 2 including portions of said sheet each projecting outward from one of said second set of edges in said upper layer.

4. A shoulder pad as claimed in claim 2 in which said first set of edges of said lower layer extend at acute angles to said transverse fold terminating thereat and portions of said upper layer each project from one of said second set of edges.

5. A shoulder pad comprising in combination a sheet of material, a fold in said sheet upon itself, an upper layer of said sheet formed by said fold, a lower layer of said sheet formed by said fold, said fold extending transversely across said sheet and interposed between said layers, a pad of material contained within the upper and lower layers of said folded sheet of material, an edge of said pad of material abutting the inner surface of said fold, a slit defining edge extending into said sheet at an angle to said fold, and a projecting portion of the said sheet adjacent said edge and extending from said fold.

6. A shoulder pad including in combination a sheet of material, a fold in said sheet upon itself, an upper layer of said sheet formed by said fold, a lower layer of said sheet formed by said fold, said fold extending transversely across said sheet and interposed between said layers, a pad of material positioned between the upper and lower layers of said folded sheet of material, a pair of slit defining edges in said sheet at one side of said shoulder pad forming angles to said transverse fold, one of said edges extending in one direction from said fold and the other of said edges extending in the opposite direction from said fold whereby said edges form an angle with each other.

7. A shoulder pad comprising in combination a sheet of material, a fold in said sheet upon itself, an upper layer of said sheet formed by said fold, a lower layer of said sheet formed by said fold, said fold extending transversely across said sheet and curved to give said shoulder pad arcuate shape, a pad of material contained within the upper and lower layers of said folded sheet of material and curved to conform therewith, a curved edge of said pad of material abutting the curved inner surface of said curved fold, a slit defining edge extending into said sheet at an angle to said fold and extending from said curved fold as an extension thereof, and a projecting portion of said sheet adjacent said edge and defined by said edge to project from said shoulder pad.

8. A shoulder pad comprising in combination

a sheet of material having a center line, said sheet being foldable on said center line, a pad of material enclosable within said sheet of material, an upper layer of said sheet formed by said fold and enclosable on said pad, a lower layer of said sheet formed by said fold and enclosable on said pad, a first slit defining edge extending into said sheet at an angle to said fold, a second slit defining edge extending into said sheet at an angle to said fold, said first and second slit defining edges being at angles to each other when said sheet of material is unfolded, and an edge of said pad material lying between said slit defining edges and abutting the inner surface of said fold.
